CASING FOR A NASAL MEDICINAL INHALER

John V. Ryden, 181 Skytop Drive, Pleasantville, N.Y., and Nial J. Quinlan, 1 Firwood Road, Port Washington, N.Y.

Filed Mar. 8, 1961, Ser. No. 64,191

Term of patent 14 years

(Cl. D83—1)

FIG. 1

We claim:

The ornamental design for a casing for a nasal medicinal inhaler, as shown.
